(57) **CLAIM**

The ornamental design for a roaster and turkey rack and lifter, as shown and described.

DESCRIPTION

FIG. 1 is a perspective view of a roaster and turkey rack and lifter, showing our new design;

FIG. 2 is a top plan view thereof;

FIG. 3 is a bottom plan view thereof;

FIG. 4 is a side elevational view of one side thereof;

FIG. 5 is an end elevational view of one end thereof;

FIG. 6 is a side elevational view of the other side thereof; and,

FIG. 7 is an end elevational view of the other end thereof.

The broken line drawing of a roaster pan in FIG. 1 is for illustrative purposes only and forms no part of the claimed design.
